UNITED STATES PATENT OFFICE.

FREDERICK S. DAVENPORT, OF ATLANTA, GEORGIA.

SIGNALING MEANS FOR TELEPHONE SYSTEMS.

No. 923,499.

Specification of Letters Patent.

Patented June 1, 1909.

Application filed April 30, 1907. Serial No. 371,113.

To all whom it may concern:

Be it known that I, FREDERICK S. DAVENPORT, a citizen of the United States, residing at Atlanta, in the county of Fulton and 5 State of Georgia, have invented certain new and useful Improvements in Signaling Means for Telephone Systems, of which the following is a specification, reference being had therein to the accompanying drawing.

10 My invention relates to signaling means in a common battery private line telephone system and it consists in the arrangements and combinations herein described.

It is a fact well known by those who have 15 had any connection with central energy systems that the charge and discharge of the condenser in the bell circuit of the subscriber's instrument will cause the bell to give a single tap whenever the receiver is removed from 20 the hook or replaced thereon. This is due to the action of the momentary current passing through the bell when the condenser is discharged or charged by the making or breaking of the circuit at the hook switch. I have 25 taken advantage of this fact to arrange a system of private lines feeding from a common battery with devices for ringing the signal bells of the several lines without the necessity of employing ordinary generators for 30 that purpose.

This device consists of an interrupter conveniently located near each subscriber's instrument, bridging the line wires and adapted to short circuit the latter intermittently 35 as the interrupter is operated. The intermittent short circuiting of the line wires of course short circuits the condenser which discharges through the bell causing a single tap, while the breaking of the line circuit puts 40 the battery again on the condenser, charging the latter and causing another tap of the bell. The rapid repetition of the charging and discharging of the condenser by means of the interrupter, will give a prolonged ringing of 45 the bell, amply sufficient to serve for signaling purposes.

My invention is illustrated in the accompanying drawings in which—

Figure 1 is a diagrammatic view showing 50 my invention as applied to a private line

telephone system. Fig. 2 is a plan view of the interrupter. Fig. 3 is a sectional view taken on the line A—A of Fig. 2, looking in the direction of the arrows. Fig. 4 is a detail view of the slotted end of the shaft and of the 55 brass contact pieces.

Referring to Fig. 1, 1 and 2 represent the line wires of a private line system. A common feed battery 3 furnishes current for talking and also for ringing the signal bells. Between the terminals of the battery 3 and the corresponding line wires are the impedance coils 4 and 4'. The signal bells 5 and 5' of the subscribers' instruments bridge the line wires 1 and 2, and the condensers 6 and 6' 60 are arranged in series with the bells in the ordinary manner. In series with the primary windings of the induction coils 7 and 7' are the transmitters 8 and 8' which are connected with the line wires 1, while hook 65 switches 9 and 9' serve to close the circuits through the transmitters. Receivers 10 and 10' are connected to the terminals of the secondary windings of the induction coils 7 and 7'. Bridging the line wires 1 and 2 at the 70 points 11, 11' and 12, 12', are the interrupters B and B' arranged to short circuit the line wires 1 and 2 and by charging and discharging the condensers 6 and 6' to ring the signal 75 bells.

80 The construction of the interrupters is as follows: A block of wood 13, having a central bore 14 extending part way therethrough is provided with lateral slots 15 and 16, the slot 15 being in the upper face of said block and 85 the slot 16 extending midway between the upper and lower surfaces thereof. Secured in the slot 15 is a spring member 17. A steel shaft 18 is journaled in the slot 16 and its outer end is bent to form a crank. The inner 90 end of the shaft 18 is provided with two intersecting slots 19 and 20 (see Fig. 4) adapted to receive brass contact pieces 21 and 22. The latter are slotted at 21' and 22' and are interjoined as shown in the figure. A second 95 spring contact member 23 is secured at 24 and is adapted to bear on the end of the shaft 18 when the latter is operated. A bearing 25 is provided for the inner end of the shaft 18, said bearing being secured at the bottom of 100

the bore. A coiled spring 26 surrounds the shaft 18 and bears at one end on a washer 27 and at the other end on the bearing 25. The spring 23 is normally out of contact with the 5 shaft end.

The spring member 17 is so arranged that the brass contact pieces engage it intermittently and as the shaft is rotated and one contact piece passes from under the spring, 10 the latter is momentarily free from any connection with the contact pieces or with the shaft, until the succeeding contact piece engages it. The springs 23 and 17 are in electrical connection with the line wires 1 and 2 15 as shown in Fig. 1.

From the above description it will be seen that when the shaft 18 is pressed against the spring 23, against the action of the coiled spring 26 and is rotated by means of the 20 crank, the line wires will be short circuited intermittently and the condensers 6 and 6' will be charged and discharged. This will ring all the bells on the line in the manner heretofore described. Upon cessation of the 25 ringing the spring 26 will force the shaft out of contact with the spring 23 so that if the spring 17 should happen to be resting on one of the contact pieces the line will not be permanently short circuited.

30 I prefer to use a circular block when the interrupter is to be used in connection with a desk instrument. The device can be secured to the bottom of the desk stand in place of the bottom piece ordinarily provided, by means of screws passing through the countersunk screw holes 28. For wall instruments I use a square block and screw it to the back board above the transmitter arm.

40 The advantages of my invention will be at once apparent. The interrupter is a simple device which admirably performs all the functions of the more complicated generator. It is easily attached and takes up little room 45 and its use in a private line system permits the employment of the common feeding battery for ringing as well as for talking purposes. Its utility has been practically demonstrated and its employment for operating 50 signal bells in the manner above described has met with entire success.

It should be observed that I am not limited to the specific form of interrupter herein shown, and may introduce multiplying gearing between the crank and the shaft as in the well known magneto hand generator, so as to produce impulses at any desired frequency. Many other non-essential changes will be obvious from the description and drawing, and 60 are clearly within the scope of my invention and of the appended claims.

Having thus described my invention, what I claim and desire to secure by Letters Patent is:

1. In a telephone system, a line circuit, a 65 plurality of signaling devices connected thereto, a common source supplying continuous current to the circuit, an inductive device associated with each signaling device, and means separate and apart from the signaling devices for charging and discharging said inductive devices from said source so as to actuate the signal devices.

2. In a central energy telephone system, a 70 pair of line wires, a common battery bridged across said line wires, subscribers' signal bells bridged across said line wires, condensers in series with said signal bells, and manually operated means to intermittently short circuit said line wires to charge and 80 discharge said condensers and thereby ring the signal bells.

3. In a central energy telephone system, a 85 pair of line wires, a common feed battery bridged across said line wires, subscribers' signal bells bridged across said line wires, condensers in series with said signal bells, and an interrupter adapted to intermittently short circuit said line wires to charge and discharge said condensers, and thereby ring 90 the signal bells, said interrupter comprising a base, a shaft journaled in said base having a crank at one end and provided with spaced contact pieces at the other end, a contact spring connected with one line wire and arranged to bear on the shaft, and a second contact spring connected with the other line wire and adapted to bear on said contact pieces.

4. In an electrical signaling system, a line 100 circuit, a source of current connected thereto, signaling devices connected to said line circuit, condensers in series therewith, and an actuating device or interrupter for the signals associated with the line, and comprising a 105 base, an adjustable shaft journaled therein and provided with intersecting slots, metal contact pieces disposed in said slots and projecting beyond the perimeter of said shaft, a spring member adapted to engage said contact pieces intermittently when the shaft is rotated, a second spring adapted to engage the ends of said contact pieces in the adjusted position of the shaft, and means operating 110 to keep the latter normally out of engagement with said second spring.

5. In an electric signaling system, a line circuit, a source of current connected thereto, signaling devices connected to said line circuit, condensers in series therewith, and an 115 actuating device or interrupter for the signals associated with the line, and comprising a block having a bore extending partly therethrough, an adjustable shaft journaled in a slot in said block, one end of said shaft carrying a crank for rotating the same, and the other end extending within said bore and having intersecting cuts, metal contact pieces 120

disposed in said cuts, a spring member secured in a second slot in said block and adapted to engage said contact pieces intermittently when the shaft is rotated, a second 5 spring secured to said block within said bore and adapted to engage the ends of said contact pieces in the adjusted position of the shaft, and a coiled spring attached to said shaft and operating to keep the latter nor-

mally out of engagement with said second 10 spring.

In testimony whereof I affix my signature in presence of two witnesses.

FREDERICK S. DAVENPORT.
